UNITED STATES PATENT OFFICE.

RICHARD T. CLARKE, OF COLUMBUS, OHIO.

GARMENT-SUPPORTER.

1,262,451.

Specification of Letters Patent. Patented Apr. 9, 1918.

Application filed September 13, 1917. Serial No. 191,208.

To all whom it may concern:

Be it known that I, RICHARD T. CLARKE, a citizen of the United States, and a resident of Columbus, in the county of Franklin and 5 State of Ohio, have invented certain new and useful Improvements in Garment-Supporters; and I do hereby declare the following to be a full, clear, and exact description of the invention, such as will enable others 10 skilled in the art to which it appertains to make and use the same.

This invention relates to improvements in garment supporters, such as are adaptable for use as combined suspenders and garters 15 for boys,—the object of the invention being to simplify and improve garment supporters of this type and to so construct the same that all strain, both of the suspenders and the garters, will come directly upon the 20 shoulder portion.

A further object is to so construct the device that it shall be comfortable to the wearer.

With these and other objects in view, the 25 invention consists in certain novel features of construction and combinations of parts as hereinafter set forth and pointed out in the claims.

The accompanying drawing is a view of 30 a garment supporter embodying my improvements.

1—1 represent the shoulder straps which are connected at their rear or back ends by a vertical back strap 2 adapted to occupy a 35 central position at the back of the wearer. The back strap may comprise two pieces of webbing stitched together with the meeting ends of the shoulder strap secured between them, and said back strap depends below the 40 meeting ends of the shoulder strap. To the lower end of this back strap, the upper ends of downwardly and laterally projecting straps 3 are secured and are made of such length as to provide extensions which form 45 garter straps, 4,—said garter straps being provided with suitable attaching devices 5 for connecting the same with the stockings of the wearer and also with adjusting buckles 13.

50 The front ends of the two shoulder straps are provided with buckles 6 to effect the adjustable connection therewith of suspender ends 7—8. Each suspender end is provided with a button 9 and similar buttons 10 are 55 located intermediate of the ends of the straps

3,—said buttons 9 and 10 being thus so located at the waist band of the trousers that they may be readily attached thereto.

The straps which form the suspender ends 8 are extended beyond the buttons 9 thereon 60 and cross the adjacent straps 3 at the upper ends of the greater portions 4 thereof (where they are secured by suitable stitching) and said garter portions 4^a provided with adjusting buckles 11 and with suitable 65 stocking attaching devices 12.

Having fully described my invention what I claim as new and desire to secure by Letters-Patent, is:

1. In a garment supporter, the combination with shoulder straps connected together at the back, and a back-strap depending from the point of attachment of the shoulder straps, of downwardly and laterally extending straps secured at their upper ends 70 to the back strap and forming garter portions at their lower ends, and two suspender ends attached to each shoulder strap, one suspender end of each pair being extended downwardly and crossing the adjacent laterally and downwardly extending strap at the upper end of the garter portion thereof and secured thereto, said suspender end extensions forming garter portions. 75

2. In a garment supporter, the combination with shoulder straps secured together at the back, and a back strap depending from the point of attachment of the shoulder straps, of downwardly and laterally extending straps secured at their upper ends 80 to the back strap and forming garter portions at their lower ends, two suspender ends attached to each shoulder strap, one suspender end of each pair being extended downwardly and crossing the adjacent laterally and downwardly extending strap at the upper end of the garter portion thereof and secured thereto, said suspender end extensions forming garter portions, and attaching means on the several suspender ends 85 90 and also on the downwardly and laterally extending straps at points intermediate the back strap and the garter portions. 95

In testimony whereof, I have signed this specification in the presence of two subscribing witnesses.

RICHARD T. CLARKE.
